APPARATUS FOR LAYING MATS ON
LANDING FIELDS

Charles H. Payne, Melbourne, Fla., assignor to
Oscar F. Arthur, Belle Vernon, Pa.
Application April 3, 1942, Serial No. 437,537

9 Claims.

(Cl. 94—39)

My invention relates to the laying of mats on areas which it is desired to use as airplane landing fields, beach aprons, temporary roads, or the like, and which would otherwise be unsuitable for such purposes, because of soft, swampy or sandy conditions of the ground.

My invention has for its object the provision of an apparatus and method whereby mats of wire mesh or the like can be laid or removed quickly, with a minimum of manual labor, certain forms of the apparatus being capable of easy application to trucks of standard makes.

Another object of my invention is to lay mats of flexible material such as wire mesh, in such manner that they will be snugly on the ground in a substantially taut condition, with no bulges or waves except for irregularities in the earth surface.

A further object is to provide apparatus for removing mats from a field and loading them on a truck, the apparatus being operable simply through movement of the truck across a mat-laid field.

Some of the forms which my invention may take are shown in the accompanying drawings wherein—

Figure 1 is a plan view of a motor truck and one form of apparatus that embodies my invention; Fig. 2 is a side view thereof; Fig. 3 is a front elevational view; Fig. 4 is a rear view; Fig. 5 is a side view of another form of apparatus embodying my invention for laying mats, but indicating the manner in which it is operated to lift a mat from the field and reload it on the truck; Fig. 6 is a rear view showing a modification of the apparatus of Fig. 5; Fig. 7 is an enlarged plan view of a portion of a mat section and one of the toothed wheels of Figs. 1 to 5 which are used in lifting and reloading the mats; Fig. 8 is an enlarged view, in side elevation, showing one of the toothed wheels and a driving sprocket therefor; Fig. 9 is a sectional plan view of a portion of the apparatus of Figs. 1 and 5; Fig. 10 is a view fragmentarily showing, on an enlarged scale, a portion of some mat sections, and the manner in which they are unitarily connected to one another; Fig. 11 shows a modification of the structures of Figs. 1 and 5, with provision of mat reloading apparatus that is operable during forward travel of the truck; Fig. 12 is a rear view thereof; Fig. 13 is a plan view of a portion of the apparatus of Fig. 11; Fig. 14 is a view taken on the line XIV—XIV of Fig. 13, and Fig. 15 is a view showing a

manner in which the mat may be drawn from a trailer truck and laid on a field.

As shown in Figs. 1 to 4, the apparatus is mounted upon a truck of conventional form that comprises the usual front and rear wheels 10 and 11; cab 12 and frame 13. A plate 14 is secured to the frame members 13 and supports a turntable 15 that has casters 16 whereby it can easily be turned and rolled forwardly and backwardly on the truck. Guide ribs 17 are provided on the plate 14 for the casters 16 when the table is rolled forwardly, to guide the turntable and prevent idle turning movement thereof when it is advanced further forwardly than as shown in Figs. 1 and 2. Such forward position will be occupied when reloading the fabric on the table as hereinafter described, and also when drawing the fabric mat from the table to spread it on the ground, if desired. The plate 14 also has a long slot 18 through which extends a stud 19 that is secured to the underside of the table 15 and has retaining nuts 20 on its lower end to prevent accidental upsetting or displacement of the turntable from the truck, the stud being movable along the slot, with the table.

Usually, it will be desired to lay mats of perhaps 12 feet in width, which is wider than the permitted width of loads traveling the highways. It will be seen that the mat 22 is much wider than the truck, and for this reason I employ the turntable 15, so that during movement along highways or in neighborhoods where there are trees or other obstructions, the turntable will be rolled on its casters 16 to turn it, and the folded mat 22 carried thereby from the full-line position to the dotted-line position indicated in Figs. 1 and 2. The table 15 is provided with ears 23 whereby either end can be connected to a truck frame member 24 by a pin 25, to anchor it during transportation.

When the truck reaches the field on which the mat is to be laid, the table is disconnected at 25 and rolled backwardly far enough to permit it to be swung to its crosswise position shown in Fig. 1. It may then be advanced somewhat toward the cab 12—perhaps further forwardly than shown in Fig. 2.

Thereupon the forward end of the mat will be pulled forwardly over the cab and to the ground in front of the wheels 10, and laying operations begin, through forward travel of the truck.

To facilitate withdrawal of the mat load from the truck, it is arranged in folds. This folding is possible because the mat is formed of a series of wire mesh panels 27 that are hingedly or piv-

totally connected as shown in Fig. 10. The adjacent edges of each panel, which extend cross-wise of the mat formed by the connected panels, has each a spiral wire 30 engaged with its end strand, and a rod 29 extends through both of these spirals, and through loops or eyes 31 formed on the ends of the marginal wires 32 of the panels. The panels can thereby be folded upon one another. As shown in Fig. 2, a series of folds 34 are first placed upon the table, thereupon this group of folds is covered by laying a series of panels thereon, as indicated by the line 35. The next succeeding panels are folded to form a group 36, and the operations repeated until a desired load weight or mat length has been placed on the truck.

Extending from a tubular member 38 that is secured to the truck frame, are a series of guide rails 39. These extend over the cab 12 and are connected at their forward ends to a tubular member 40, that is in turn secured to the ends of the truck frame or to a bumper, as may be desired. Guide rails 42 and 43, of angular form in cross section, are provided, for vertically supporting the edges of the mat and to also guide such edges and prevent lateral shifting of the mat when it is being drawn along the guide rails. The rear ends of the rails 42 and 43 are connected to short rods 44 and 45 respectively that telescope into the member 38, to make adjustments for various widths of fabric. The rods and the rails are held in their adjusted positions by pins 46 that extend through holes in the sleeve bar 38 and in the rods 44 and 45. Intermediate their ends, the rails 42 and 43 are connected to rods 47 and 48 respectively, that telescope into a tubular shaft 49 that is rotatably supported in the rails 39. At their forward ends, the rails 42 and 43 are connected with rods 50 and 50a, respectively, that have telescopic engagement with the tubular bar 40.

In order to facilitate laying a mat section along a precisely-defined line or in proper proximity to the edge of a previously-laid section, it being difficult for the truck driver to steer the truck along a precisely-defined straight line, I provide means for guiding the mat as it is drawn to the ground through forward movement of the vehicle (Figs. 1 and 9). To this end, a bracket arm 51 is secured to the frame 13 and serves as a pivotal support and fulcrum for a lever 52. This lever may be operated by a man sitting on a lazy-board 53 which is slidable inwardly and outwardly on the underside of the turntable 15. A similar lazy-board 54 is provided at the opposite side of the table, and these boards can be used as platforms on which workmen may stand when necessary in connection with the reloading of the fabric on the turntable, for example. The forward end of the lever 53 is pivotally connected to a bar 55 that at its ends has holes through which pins or bolts 56 may be inserted. These pins extend through small angles 57 that are welded to the guide rails 42 and 43. The guide rails are therefore adjustable longitudinally of the bar 55, to various widths of fabric. When the fabric mat is being laid upon the ground through advancing movement of the truck, the operator will move the lever 52 to flex or slide the forward ends of the guide rails 42-43 and thus enable the fabric to be guided along a definite line as it is being fed to the ground, notwithstanding slight deviations in the path of truck travel. This is particularly important where a mat such as A of Fig. 10 is being laid alongside a previously-laid mat B, so that the

edges of the mats will be in proper proximity to one another.

In the operation of the apparatus, the forward edge of the mat will be drawn from the stack on the truck, along the tops of the guide rails and the front edge thereof inwardly beneath the front wheels 10 of the truck. Forward travel of the truck will cause the mat to be drawn from the table 15 and pressed firmly upon the ground in a taut condition and with no bulges except those produced by hard surface irregularities of the ground.

In soft ground or sand where the mat will usually be laid, it will be drawn and pressed down into small protuberances of earth, and in any event, will be pressed so snugly to the ground that it will usually lay without shifting its position after the truck has passed over it. When one long mat (perhaps 1,000 feet) has been laid, such as the mat B, another load of folded fabric will be placed on the truck and it will run alongside the mat B to lay the mat A. These mats have loops or rings 60 welded to their edge strands 32, so that after the sections A and B are laid, rods 61 can be inserted through the loops to tie the mat sections A and B together. The laying of the mats in front of the truck as the truck progresses, not only results in the mat being laid in a tensioned flat position as above explained, but is further advantageous in that the driver of the truck can conveniently lay the mat with greater accuracy than if it were simply permitted to trail off the rear end of the truck as the truck progresses. In the latter case, the mat would tend also to lie in loose waves and not be pressed into snug contact with the ground. Another advantage of laying the mat in advance of the truck is that it will provide a running surface for the truck, in sand or soft ground.

Provision is also made for taking up a mat from the ground and reloading it on the truck. To this end, a sprocket wheel 63 is secured to the hub of one of the wheels 11 and drives a sprocket chain 64, which in turn drives a sprocket wheel 65 (Fig. 3) that is secured to a shaft 66 journaled on the underside of the truck frame. The shaft 66 carries a sprocket pinion 67 that through a chain 68 drives a sprocket wheel 69, which is secured to the tubular shaft 49 that carries sprocket wheels 71. The teeth of the sprocket wheels 71 engage with the stays of the mesh as shown more clearly in Fig. 8, so that as the truck is driven backwardly, the sprocket wheels will draw the mat from the ground back across the guide rails 39-42-43 and push it to the body of the truck, where it can again be stacked or folded as by workmen standing on the lazy-boards 53-54. The chains 64 and 68 may be disconnected or removed when laying the fabric, since the forward movement of the vehicle and the weight of the front wheels 10 on the mat will cause it to be drawn from the truck body, the sprockets 71 in that case turning with idling movement. If desired, however, the chains can be left in place and the sprocket wheels 71 driven when moving the truck forwardly during laying of the fabric.

In Fig. 5 I show a somewhat different arrangement than that disclosed in Figs. 1 to 4. In this instance, the groups of folds of the fabric are arranged in upright position as indicated at 73 instead of horizontally as in Fig. 2. The fabric can be drawn from those upright stacks through advancing movement of the vehicle, as in the case of Figs. 1 and 2. However, the arrows on this Fig. 5 indicate the truck as being driven

rearwardly, in the process of lifting the fabric from the ground and reloading it on the truck, the sprocket chains 64 and 68 being driven as above indicated, through rearward movement of the vehicle. In order to facilitate the reloading of the fabric on the rear end of the turntable 15, guide bars 74 are provided that are secured at their forward ends to a cross bar 75 which is in turn carried by guide rails such as the rails 39 of Fig. 1. The bar 74 has extensible sections 76 that telescope therewith, so that the fabric will be delivered at a desired distance rearwardly of the cab, as indicated by the arrow 77. As the loading progresses, the bar sections 76 will be telescoped forwardly into 74. In laying a mat, these bars will be contracted in telescoped relation, to facilitate withdrawal of the mat from the truck.

Referring now to Fig. 6, I show a modified form of truck body which need not have a turntable. In this instance, the truck frame has a tubular cross member 78 carried near its rear end for telescopingly receiving bars 79 which are adjustable inwardly and outwardly and may be locked in adjusted position by set screws 80. These bars carry the rear ends of angles 81 that at their forward ends are welded to guide rails 82 that correspond to the guide rails 42 and 43 of Fig. 1. The rails 81 are therefore adjustable laterally of the truck along with the rails 42-43. In transporting a load of fabric to the place of installation, the members 81 and 82 will be adjusted to their contracted positions, close to the edges of the truck, and the folded fabric will be so placed that the layers of fold will extend longitudinally of the truck, so that in the case of 12-foot wide fabric, for example, it will not project beyond the edges of the truck. When the field is reached, the rails 81 and 82 will be expanded to 12 feet spacing, for example, as shown in Fig. 6, and the piles of fabric will then be turned to the position shown in Fig. 1, with the edges thereof supported on the angles 81. If this turning is to be done manually, the stacks of folds will be discontinuous. That is, the stacks will be formed of separated lengths of fabric, but as unloading progresses, the rear end of the fabric forming each stack will be connected by the workmen to the leading edge of the succeeding stack or series of folds, by inserting the connecting rods 29 (Fig. 10).

In Figs. 11 to 14 I show an arrangement whereby a mat can conveniently be taken up and reloaded during forward traveling movement of a truck. In this instance, the mat can be laid from the truck body by passing it forwardly over guide rails 85 and under the front vehicle wheels during forward travel of the vehicle, as explained in connection with Figs. 1 and 2. By the apparatus shown in Fig. 11, a mat can be lifted and removed from a field through forward travel of the truck which can, of course, be more easily and accurately operated in that manner than in a backward direction. To this end, I provide guide rails 86 which are curved downwardly at their rear ends and which are adjustable laterally to various widths of fabric, by reason of the telescoping fit between their supporting bars 87 and a sleeve shaft 88 that is carried by the truck frame, the adjustments being maintained by the use of pins 89 that extend through holes in the sleeve 88 and into holes in the rods 87, as in the case of the lateral adjustment of the rails 42-43 of Fig. 1, the rods being flanged at their outer ends to hold the rails in place thereon.

The sleeve 88 serves as a shaft and to this end the rods 87 are rotatable in the guide rails 86 so as to permit rotation of the sleeve. The sleeve is provided with a sprocket wheel 90 that is driven from one of the truck wheels 91 by a sprocket chain 92 that extends around a sprocket wheel 93 on the truck wheel. Other suitable driving means could be provided for the sprocket wheel 90, as for example, a power take-off from the engine shaft.

Mesh-engaging sprockets 94 are mounted on the shaft 88 and have their teeth staggered for effective engagement with the mesh wires at a suitable number of points. Bearings 95 are provided for the shaft 88, such bearings being mounted in brackets 96 that are secured to the truck frame.

It will be seen that in removing a mat from a field, the truck will be driven forwardly in the usual manner, on the mat, and the rear free end of the mat will be lifted into engagement with the sprocket wheels 94, so that during continued movement of the truck, the mat 97 will be raised from the ground progressively and pushed onto the body of the truck. If a considerable quantity of mat is to be thus removed, workmen standing on the truck or alongside thereof, will arrange the mat into folds 98 as it reaches the truck body, and these folds can be arranged in tiers, as shown either in Fig. 2 or Fig. 5. The mat thus loaded can be unloaded and laid simply through backward movement of the truck, or through forward movement thereof. The latter procedure is, of course, preferable, and in that case the mat will be fed forwardly over the guide rails 85 as the truck moves forward.

Referring now to Fig. 15, I show an arrangement whereby much larger supplies of mat can be laid without interruption for loading additional supplies on a truck. In this instance, a truck 100 can initially contain a supply of the mat folds from which the mat will be drawn and laid in front of the vehicle as the vehicle advances, after the manner described in connection with Figs. 1 to 10. An additional supply of mat will be carried on a trailer truck 101, the forward end of this additional mat supply being connected to the rearmost end of the mat that was carried on the truck 100, and the trucks connected by a suitable coupling bar 102. It will be understood that the supplies of mats on the truck 100 and 101, or on the truck 101 alone, can be arranged in stacks or tiers as shown in Figs. 2 and 5.

I claim as my invention:

1. Mat-laying apparatus comprising a wheeled vehicle, means associated with the vehicle for carrying a supply of flexible mat material, guide rails positioned to direct the material from said source of supply to the ground at one end of the vehicle, whereby when an end of the mat is brought into position beneath the wheels at one end of the vehicle, traveling movement of the vehicle in that direction will effect withdrawal of the material from said supply source, and sprocket wheels or the like operable during movement of the vehicle in the reverse direction, to move the material in the opposite direction as it is released by the said wheels.

2. Mat-laying apparatus comprising a vehicle, means associated with the vehicle for carrying a supply of flexible mat material, guide rails positioned to direct the material from said source of supply to the ground at one end of the vehicle whereby when an end of the mat is brought into position beneath the wheels at one end of the ve-

hicle, traveling movement of the vehicle in that direction will effect withdrawal of the material from said supply source, and means driven from one of the vehicle wheels when traveling in the reverse direction, to move the material in the opposite direction as it is released by the said wheels.

3. Mat-laying apparatus comprising a vehicle having an operator's station, means associated with the vehicle, rearwardly of said station, for carrying a supply of flexible material, guide rails positioned above said station and extending forwardly and downwardly in position to direct the material from said source of supply to the ground at one end of the vehicle, whereby when an end of the mat is brought into position beneath the wheels at one end of the vehicle, traveling movement of the vehicle in that direction will effect withdrawal of the material from said supply source, and a lifting device for withdrawing the mat from the ground and directing it rearwardly of said guide rails, upon reverse travel of the vehicle.

4. Mat-laying apparatus comprising a vehicle having an operator's station, means associated with the vehicle, rearwardly of said station, for carrying a supply of flexible material, guide rails positioned above said station and extending forwardly and downwardly in position to direct the material from said source of supply to the ground at one end of the vehicle whereby when an end of the mat is brought into position beneath the wheels at one end of the vehicle, traveling movement of the vehicle in that direction will effect withdrawal of the material from said supply source, and means for withdrawing the mat from the ground and directing it rearwardly of said guide rails, upon reverse travel of the vehicle, the said means comprising sprocket wheels mounted on the guide rails and driven from one of the vehicle wheels.

5. The combination with a vehicle which is

movable on a mat from one end to its other end, of means located at the rear end of the vehicle for progressively lifting and stowing portions of the mat over which the vehicle has passed, the said means comprising guide rails and a rotatably mounted sprocket at the rear end of the vehicle.

6. The method of laying mats to form a supporting surface on soft ground and the like, which comprises storing a supply of the mat material on a vehicle, placing an end of the material on the ground and under ground-engaging members of the vehicle at one end of the vehicle, and moving the vehicle in a direction forwardly of said end and upon succeeding portions of the mat while supporting the material for progressive withdrawal thereof from the vehicle.

7. The method of laying mats to form a supporting surface on soft ground and the like, which comprises hingedly connecting a series of mat sections, folding them against one another and storing the series on a wheeled vehicle, in relatively folded arrangement, placing an endmost section under the wheels at one end of the vehicle, and moving the vehicle in a direction forwardly of said end while supporting the material for progressive withdrawal thereof from the vehicle.

8. The method of placing a mat-like supporting surface under the wheels of vehicles while they are traveling, which comprises stowing a mat on a vehicle, at a plane above the wheels, and progressively discharging the mat to the ground in advance of the vehicle, through engagement of the wheels with a forward portion of the mat.

9. Apparatus for laying mats on terrain, in advance of vehicle wheels, which comprises the combination with a vehicle of means thereon for supporting a mat, and means for guiding the mat to points forwardly of the wheels as it is drawn from the vehicle through forward movement of the vehicle when its wheels are upon a forward portion of the mat.

CHARLES H. PAYNE.
